(57) **CLAIM**

The ornamental design for a communication hat, as shown and described.

DESCRIPTION

FIG. 1 is a front perspective view of a communication hat, showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is an enlarged detail view from line 9 in FIG. 1;

FIG. 10 is an enlarged detail view from line 10 in FIG. 2; and,

FIG. 11 is an enlarged detail view from line 11 in FIG. 2. The broken lines in the drawings illustrate the portions of the communication hat, which form no part of the claimed design.

The dash-dot-dash broken lines in FIGS. 1, 2, 9, 10, and 11 define the boundaries of the enlarged figure views and form no part of the claimed design.
